UNITED STATES PATENT OFFICE.

KIMBALL B. FLETCHER, OF LANCASTER, NEW HAMPSHIRE, ASSIGNOR TO THOMPSON MANUFACTURING COMPANY.

PULP-SEPARATOR.

SPECIFICATION forming part of Letters Patent No. 735,080, dated August 4, 1903.

Application filed October 9, 1902. Serial No. 126,374. (No model.)

To all whom it may concern:

Be it known that I, KIMBALL B. FLETCHER, a citizen of the United States, and a resident of Lancaster, in the county of Coos and State 5 of New Hampshire, have invented certain new and useful Improvements in Pulp-Separators, of which the following is a specification.

My invention relates to machines for reducing the consistency of wood-pulp by removing a portion of the water or other liquid mixed with the pulp either in the process of grinding or digesting by chemicals or in subsequent stages of manufacture.

It consists, essentially, in certain mechanism for automatically regulating the flow of the liquid pulp, keeping the pulp at a uniform height, and rendering the operation of the machine steady and uniform.

In the accompanying drawings, Figure 1 is 20 a side elevation of my machine. Fig. 2 is a vertical transverse section in a line parallel with the side of the machine. Fig. 3 is a detail of a portion of the regulating mechanism. Fig. 4 is a top view of the machine with the 25 cover removed.

A is a rectangular water-tight receptacle or tank, preferably made of wood, within which is the vat B, the bottom of which is substantially semicircular in cross-section 30 and the front and back walls of which are below the level of the top of the tank A.

A short distance from the front wall of the tank A and forming a part of the front wall of the vat B is the upright distributing-board C, forming, with the front and side walls of the tank A, a receiving-trough D, into which the liquid pulp flows through the opening E and, striking against the distributing-board C, is distributed over its surface and flows in 40 a uniform sheet over its top into the vat B.

In the vat B is a cylindrical screen F, mounted on a shaft G, having its bearings in the sides of the vat, to which rotary motion is given by means of the driving-pulley G' 45 through the medium of gears G² and G³. The shaft is placed somewhat to the rear of the middle of the vat, making the periphery of the cylindrical screen eccentric to the curve of the bottom of the vat. The screen F is 50 covered with wire-cloth, which is of a suit-

able mesh to allow the water from the pulp to drain readily into the interior of the cylinder.

The cylindrical screen F is open at both ends. Opposite to the lower part of the cylinder are openings in the sides of the vat B, communicating with side vats I I, one at each end of the cylinder. Suitable packing-rings, preferably made of canvas and not shown in the drawings, encircle the ends of the cylinder and prevent the pulp from passing from the main body of the vat through the openings into the side vats I I.

A couch-roll J, having its surface covered with felt, is mounted above the screen F and rests upon it with sufficient pressure to be rotated by the movement of the screen. The ends of the shaft upon which the couch-roll is mounted are supported by boxes K, sliding in vertical ways K' and suspended from springs K², which relieve the screen from the full weight of the couch-roll. As the cylindrical screen F revolves a certain amount of the thickened pulp from which the water has been drained is taken up on its surface, from 75 which it is removed by the couch-roll J. As the couch-roll J revolves the pulp on its surface comes in contact with the wooden blade or "doctor," by which it is scraped off into the discharge-trough M, from which it is removed in any convenient manner. If it is desired that the pulp should be discharged from 80 the vat B in a liquid form, it is allowed after passing under the cylinder F to flow over the back side of the tank into the trough M. If, 85 however, the pulp is to be reduced to a comparatively solid form, the back side of the vat B is raised by an extension-board N, whose ends slide in vertical guides in the ends of the vat B and which is raised or lowered by any convenient means. The pulp is then held back in the vat B and the solid portions removed by the action of the couch-roll, as above described. The liquid strained 90 from the pulp by the action of the screen F passes into the side vats I I and thence through elbow-pipes O O, which are connected by a cross-trough P, so that the liquid from both ends of the cylinder may be discharged from a common outlet. In each of the elbow-pipes 100

O O is a gate O', mounted on a vertical shaft Q, extending to a point near the top of the tank A. By means of these gates the passage of the liquid through the elbow-pipes is regulated. The opening or closing of these gates is effected by means of the cylindrical float R in the vat B. This float consists of a hollow metallic cylinder with closed ends adapted to float at or near the surface of the pulp in the vat B. At the ends of the float are projections fitting loosely in vertical guides R', attached to the inside of the vat B. At each end of the float is an upwardly-projecting arm R², pivoted to a bell-crank lever R³, which operates an arm R⁴ on the outside of the tank A, which in turn is pivoted to the crank R⁵, attached to the upper end of the vertical shaft Q, upon the lower end of which the gate O' is mounted. The arrangement and operation of the parts are such that when the pulp begins to accumulate in the vat B the float R rises, thereby opening the gates O' and permitting the liquid to flow more rapidly from the interior of the cylindrical screen F, thus accelerating the operation of the screen in removing the liquid from the pulp. On the other hand, when the level of the pulp in the vat B falls below the normal level the float R falls, thereby closing the gates and checking the outward flow of liquid, thus retarding the action of the screen F. By these means the pulp in the vat B is automatically kept at a uniform level and the flow of the pulp is uniform and constant.

Attached to the upper end of the shaft Q is a horizontal arm S, projecting radially over a notched bar T in the form of the segment of a circle. The arm S is slotted, and in the slot is pivoted a lock-bar S', having a handle S² and a downwardly-projecting spur adapted to engage in the notches of the segment-bar T. By these means the gates O² may be turned and set permanently in any desired position independently of the action of the regulating-float R.

What I claim, and desire to secure by Letters Patent, is—

1. In a machine of the class described a vat B, a revoluble cylindrical screen F in said vat communicating at each end with a side vat I provided with a discharge-pipe O, in combination with gates O' in said discharge-pipes for regulating the flow of the water through the same and means for operating said gates, substantially as described.

2. In a machine of the class described, a vat B, a revoluble cylindrical screen in said vat communicating at each end with a side vat I provided with a discharge-pipe O having a gate

O', means for opening and closing said gates, 60 consisting of the float R adapted to be moved vertically by changes in the depth of the pulp in the vat B and means for communicating the movement of said float to said gates substantially as described. 65

3. In a machine of the class described a vat B, a revoluble cylindrical screen F in said vat communicating at each end with a side vat I provided with a discharge-pipe O having a gate O', a float R adapted to be moved vertically by the changes in the depth of the pulp in the vat B, guides R' for regulating the movements of said float and means for communicating the movements of said float to said gates substantially as described. 70

4. In a machine of the class described, a vat B, a revoluble cylindrical screen F in said vat communicating at each end with a side vat I having a discharge-pipe O a gate O' in said discharge-pipe mounted on a shaft Q and a float R adapted to be moved vertically by the changes in the depth of pulp in the vat B, in combination with an upright arm R² attached to each end of said float and pivoted to a bell-crank lever R³ and arm R⁴ operated by said lever and connecting it with the crank R⁵ on the gate-shaft Q substantially as described. 75

5. In a machine of the class described a vat B, a revoluble cylindrical screen in said vat communicating at each end with a side vat I having a discharge-pipe O and gates in said discharge-pipes for regulating the flow of liquid from said screen in combination with means for adjusting the position of said gates consisting of the arm S attached radially to the gate-shaft Q and provided with a downwardly-projecting lock-bar S' engaging the notched segment-bar T, substantially as described. 80

6. In a machine of the class described a vat B, a revoluble cylindrical screen in said vat communicating at each end with a side vat I having a discharge-pipe O and gates in said discharge-pipes for regulating the flow of liquid from said screen, in combination with means for adjusting the position of said gates consisting of the slotted arms S attached radially to the gate-shafts, each arm having a downwardly-projecting lock-bar S' pivoted in said slot and engaging the notched segment-bar T, substantially as described. 85

In testimony whereof I have hereunto subscribed my name in the presence of two witnesses.

KIMBALL B. FLETCHER.
